UNITED STATES PATENT OFFICE.

CHARLES L. SEBRING, OF SEBRING, OHIO, ASSIGNOR TO THE SEBRING POTTERY COMPANY, OF SEBRING, OHIO, A CORPORATION OF OHIO.

DESIGN FOR A PLATE OR SIMILAR ARTICLE.

Application filed July 17, 1923. Serial No. 6,792. Term of patent 14 years.

To all whom it may concern:

Be it known that I, CHARLES L. SEBRING, a citizen of the United States, residing at Sebring, in the county of Mahoning and State of Ohio, have invented a new, original, and ornamental Design for Plate or Similar Article, of which the following is a specification, reference being had to the accompanying drawing, forming part hereof.

Figure 1 is a plan view of a plate embodying my new design; and

Fig. 2, a side elevation of the same.

I claim:

The ornamental design for a plate or similar article substantially as shown.

CHARLES L. SEBRING.
